FIG. 2 is a front view thereof.
FIG. 3 is a left side view thereof.
FIG. 4 is a right side view thereof.
FIG. 5 is a top view thereof.
FIG. 6 is a bottom view thereof.
FIG. 7 is a perspective view of switch according to a second embodiment of our new design.
FIG. 8 is a front view thereof.
FIG. 9 is a left side view thereof.
FIG. 10 is a right side view thereof.
FIG. 11 is a top view thereof.
FIG. 12 is a bottom view thereof.
FIG. 13 is a perspective view of switch according to a third embodiment of our new design.
FIG. 14 is a front view thereof.
FIG. 15 is a left side view thereof.
FIG. 16 is a right side view thereof.
FIG. 17 is a top view thereof.
FIG. 18 is a bottom view thereof.
FIG. 19 is a perspective view of switch according to a fourth embodiment of our new design.
FIG. 20 is a front view thereof.
FIG. 21 is a left side view thereof.
FIG. 22 is a right side view thereof.
FIG. 23 is a top view thereof.
FIG. 24 is a bottom view thereof.
FIG. 25 is a perspective view of switch according to a fifth embodiment of our new design.

FIG. 26 is a front view thereof.
FIG. 27 is a left side view thereof.
FIG. 28 is a right side view thereof.
FIG. 29 is a top view thereof.
FIG. 30 is a bottom view thereof.
FIG. 31 is a perspective view of switch according to a sixth embodiment of our new design.
FIG. 32 is a front view thereof.
FIG. 33 is a left side view thereof.
FIG. 34 is a right side view thereof.
FIG. 35 is a top view thereof.
FIG. 36 is a bottom view thereof.
FIG. 37 is a perspective view of switch according to a seventh embodiment of our new design.
FIG. 38 is a front view thereof.
FIG. 39 is a left side view thereof.
FIG. 40 is a right side view thereof.
FIG. 41 is a top view thereof.
FIG. 42 is a bottom view thereof.
FIG. 43 is a perspective view of switch according to an eighth embodiment of our new design.
FIG. 44 is a front view thereof.
FIG. 45 is a left side view thereof.
FIG. 46 is a right side view thereof.
FIG. 47 is a top view thereof; and,
FIG. 48 is a bottom view thereof.
